UNITED STATES PATENT OFFICE.

ISAAC J. MARCUSE, OF RICHMOND, VIRGINIA, ASSIGNOR TO AMERICAN CAN COMPANY, OF NEW YORK, N. Y., A CORPORATION OF NEW JERSEY.

SHEET-METAL CAN.

No. 810,211.

Specification of Letters Patent.

Patented Jan. 16, 1906.

Application filed July 19, 1905. Serial No. 270,380.

To all whom it may concern:

Be it known that I, ISAAC J. MARCUSE, a citizen of the United States, residing in Richmond, in the county of Henrico and State of Virginia, have invented a new and useful Improvement in Sheet-Metal Cans, of which the following is a specification.

My invention relates to improvements in sheet-metal cans, and more particularly to cans designed for containing smoking-tobacco for pipes or cigarettes or other articles which may be poured out of the can when desired for use.

The object of my invention is to provide a sheet-metal can of a neat, simple, efficient, and durable construction having a removable cap closing the opening in the top of the can through which the can is filled and in which the removable cap itself is furnished with a small or pouring opening and a movable plate for closing the same, so that the contents of the can may be conveniently poured out, as required for use, which may be cheaply manufactured, and in which the movable closing-plate will be suitably guided and properly supported. My invention consists in the means I employ and herein shown and described for practically accomplishing this object or result.

In the accompanying drawings, forming a part of this specification, Figure 1 is a perspective view of a can embodying my invention. Fig. 2 is a plan view. Fig. 3 is a vertical section on line 3-3 of Fig. 2. Fig. 4 is an inside plan view of the removable cap, and Fig. 5 is an enlarged detail section of the cap.

In the drawings, A represents the body of the can or vessel, B its top or upper head, and C its bottom or lower head. The body A has preferably a lock or folded side seam 'a' at one of the corners of the can, and the head B is furnished, preferably, with a countersink b and flange b', united to the body A by a rolled, folded, or other seam a'. The bottom C is also preferably furnished with a countersink c and flange c', united to the body A by a folded, rolled, or other seam a'.

The top or upper head B is furnished with an upwardly-projecting neck or cylindrical flange b², surrounding the filling-opening B' in the can and having at its upper edge an inwardly and horizontally projecting flange b³. The neck b² of the top is preferably furnished with screw-threads b⁴ to receive the

removable cap D, which has a depending flange d, furnished with screw-threads d', to engage the screw-threads on the integral neck b² of the top or upper head B of the can. The removable screw-cap D is provided with a small or segmental pouring-opening D' at one side of its center and on its inside with a rotary closing-plate secured to the cap D by a pivot f for opening and closing the pouring-opening in the cap. When the screw-cap is applied to the screw-top of the can, the rotary closing-plate F fits between and is guided and firmly supported on the inside by the horizontal flange l³ of the screw-neck b² of the top B of the can and upon the outside by the marginal portion d⁵ of the removable cap D adjacent to the opening D' in the cap. To further guide and support the rotary sector-shaped closing-plate F, it is furnished with an integral lip f' near its circular edge f², which fits on the outside of the circular marginal portion or rim d⁵ of the cap D. This integral lip f² also serves as a stop to limit the rotary movement of the closing-plate F by its engagement with the curved ends D² D² of the opening D' in the cap D. The rotary closing-plate F is also preferably furnished with an integral projection f³, stamped up therein for engagement of the thumb or finger nail to facilitate the turning of the rotary closing-plate, although the lip f² will also answer for this purpose. The pivot f of the rotary closing-plate F may preferably be a rivet, which after being inserted is upset to secure the rotary closing-plate to the screw-cap D. As the rotary closing-plate fits between the screw-cap and the inturned margin or horizontal flange b³ of the neck b², it will be understood that the rim or peripheral portion of the rotary plate is thus firmly guided and supported on both sides or above and below, so that there is no danger of the thin sheet-metal sector-shaped closing-plate being punched through or bent or distorted out of shape, and by this means I am enabled to produce a very neat and convenient, strong, and durable can for containing smoking-tobacco or other articles and one which may also be manufactured at small cost.

I claim—

1. A tobacco or other can having a top or upper head furnished with a screw-threaded neck, provided with an inwardly-projecting flange at its upper edge, and a screw-cap hav-

ing a segmental pouring-opening therein, and a rotary segmental closing-plate inside and pivoted to said screw-cap and fitting between and guided and supported by the screw-cap 5 on the outside and said inturned flange of said screw-neck of the can-top on the inside, said rotary closing-plate having an integral lip fitting outside and engaging the marginal portion of the screw-cap adjacent to said 10 opening therein, substantially as specified.

2. In a can, the combination with a top or upper head having a screw-neck provided with an inturned flange at its upper edge, of a screw-cap having a segmental opening therein, and a rotary closing-plate fitting inside 15 the cap, and guided and supported at its outer circular portion by the inturned flange on said screw-neck, substantially as specified.

3. In a can, the combination with a top or upper head having a screw-neck provided with an inturned flange at its upper edge, of a screw-cap having a segmental opening therein, and a rotary closing-plate fitting inside 20

the cap, and guided and supported at its outer circular portion by the inturned flange on 25 said screw-neck, said closing-plate having an integral lip fitting outside and engaging the marginal rim portion of the screw-cap, substantially as specified.

4. In a can, the combination with a top or upper head having a screw-neck provided with an inturned flange at its upper edge, of a screw-cap having a segmental opening therein, and a rotary closing-plate fitting inside 30 the cap and guided and supported at its outer circular portion by the inturned flange on said screw-neck, said closing-plate having an integral lip fitting outside and engaging the marginal rim portion of the screw-cap, said rotary closing-plate having also a projection 35 for engagement of the nail to turn the same, substantially as specified.

ISAAC J. MARCUSE.
